UNITED STATES PATENT OFFICE.

LEON A. WITTER, OF LAKESIDE, OHIO

FUEL-FEED-CONTROL MECHANISM.

Application filed August 19, 1926. Serial No. 130,187.

My invention relates to improved fuel control mechanism for internal combustion engines adapted to regulate the delivery of fuel thereto in such a manner that fuel is delivered to the engine as needed and when needed but is automatically cut off therefrom upon the stopping of the engine or upon the discontinuance of the supply of lubricant to the engine.

10 My improved control mechanism is inserted in the fuel feed line which leads to the engine. It is responsive to the pressure in the lubricating system with which the engine is provided whereby, during the time 15 the engine is running and the needed supply of lubricant is being furnished to the engine, fuel is supplied in the required amount. If the engine is stopped or if the lubricant supply falls below a predetermined amount, my improved device automatically operates to shut off the supply of fuel. It therefore serves to prevent the running of the engine when dry and prevents 20 the not uncommon occurrence of the burning out of bearings and injury to the mechanism caused by the running of the engine upon an insufficient supply of oil.

My improved device is simple in construction, inexpensive to manufacture, positive in 30 its operation, and effectively serves to perform the purpose for which it is intended to be employed. Further advantages and meritorious features of my invention will more fully appear from the following description of the preferred embodiment illustrated in the accompanying drawing and 35 defined in the appended claims.

In the drawings:

Fig. 1 is an elevation of an internal combustion engine equipped with my improvement.

Fig. 2 is a vertical sectional view through my invention.

Fig. 3 is a fragmentary vertical sectional view taken on the same line as Fig. 2 with the valve mechanism open.

My invention is here illustrated in association with an internal combustion engine of the character commonly used in automobile construction. A plurality of combustion chambers are provided which are furnished with fuel from a manifold indicated as 12, the cylinder block being indicated as 10. It is common practice to pro-

vide a carburetor such as is indicated as 14 to which a fuel supply pipe 16 leads from a suitable source of fuel supply not shown in the drawing.

I prefer to build my invention in the form of a connection suitable to be readily inserted in the fuel feed line at a convenient place. It is shown as comprising a fuel container having a lower barrel section 18 provided with a removable screw-threaded cap 20. The barrel has an inlet 22 which is suitably connected in the fuel feed line 16 that leads to the source of fuel supply and an outlet 24 that is suitably connected in the fuel feed line which leads to the carburetor.

The inlet 22 terminates in a standpipe 24, which has a fuel outlet 26. The standpipe is interiorly recessed as at 28. A valve 30 is provided to regulate the flow of fuel from the standpipe to the barrel 18. This valve 35 has a stem 32 that extends upwardly through a passageway 34 in the standpipe. A spring 36 is provided. One end of the spring engages the standpipe and the opposite end engages a nut 38 on the valve 40 stem. This spring holds the valve to its seat thereby normally preventing the flow of fuel into the barrel.

The valve, while held normally closed by the spring 36, is adapted to be opened by a 45 diaphragm 40. This diaphragm is gripped between the cap 20 and the upper edge of the barrel 18. Suitable gaskets 42 may be provided. The normal position of the diaphragm is concave upwardly as shown in 50 Fig. 2. A downwardly concave guard 44 is provided. This guard has an opening 46 through which the valve stem 32 extends. The diaphragm carries an axial lug 48 which engages the tip of the valve stem and when 55 the diaphragm is moved downwardly opens the valve.

A conduit 50 leads from the upper end of the casing above the diaphragm to the oil pump 52. This oil pump is driven by the 60 engine and is a part of the provided lubricating system which supplies lubricant to the engine under pressure created by the pump. Upon operation of the pump, lubricant pressure is created in the pipe 50. This 65 forces the diaphragm 40 downwardly against the convex guard 44 upon which the diaphragm rests for support and opens the valve 70.

2
30 against the resistance of spring 36 and permits the flow of fuel through the barrel to the carburetor and to the engine.

What I claim is:

- 5 1. The combination in an internal combustion engine having a fuel feed line and a lubricant pressure line, a fuel container located within the feed line provided with an inlet terminating in a standpipe above the
- 10 floor of the container and an outlet likewise positioned above the floor of the container, a valve within the standpipe held yieldingly upwardly to close the fuel passageway therethrough, said valve having a stem extending
- 15 above the standpipe, a diaphragm positioned within the container above the standpipe open on one side to lubricant pressure and provided with a part engaging the stem of said valve to depress the same to open the
- 20 valve.
2. In an internal combustion engine having a fuel feed line and a lubricant pressure line, a container within the fuel feed line, said container having an inlet and an outlet
- 25 whereby a limited supply of fuel is normally maintained within the container, said inlet including a standpipe projecting upwardly from the floor of the container and provided with an outlet spaced above the floor of the
- 30 container, a valve within the standpipe to regulate the flow of fuel through said container, said valve extending above the standpipe and provided with a spring seated on top of the standpipe to hold the valve upwardly and closed, and a diaphragm within

the container open on one side to the lubricant pressure and provided with a part adapted to engage the valve to depress the same to the open position controlling said valve.

3. In an internal combustion engine having a fuel feed line and a lubricant pressure line, a fuel container within the feed line having an inlet and an outlet communicating therewith positioned so that a limited quantity of fuel is normally maintained therein, said container having a diaphragm dividing the same into two compartments, one compartment adapted to serve as a container for fuel, the second compartment open to the lubricant pressure line and means within the fuel compartment associated with the diaphragm to regulate the flow of fuel therethrough.

4. In an internal combustion engine, a fuel feed line, a lubricant pressure line, a fuel container within the feed line having an inlet and an outlet for fuel arranged so that a determined quantity of fuel is normally maintained within said container, a valve to control the flow of fuel through said container, a diaphragm responsive to lubricant pressure connected with said valve to open the same when subjected to a determined lubricant pressure and means operable upon the release of said pressure to close said valve.

In testimony whereof, I sign this specification.

LEON A. WITTER.
